C. S. LABOFISH.

TYPE WRITING MACHINE,

APPLICATION FILED JUNE 10, 1918.

1,317,796.

Patented Oct. 7, 1919.

FIG. 1

UNITED STATES PATENT OFFICE.

CHARLES S. LABOFISH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,317,796.

Specification of Letters Patent.

Patented Oct. 7, 1919.

Application filed June 10, 1918. Serial No. 239,226.

To all whom it may concern:

Be it known that I, CHARLES S. LABOFISH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to margin stop mechanism.

The main object of my invention, generally stated, is to improve such mechanism, 15 and provide simple and efficient means for affording an automatic control thereof so that writing may be produced at predetermined intervals within the margin.

In preparing various documents, such, for 20 example, as specifications for applications of Letters Patent, it is desirable to number the lines. It is customary to number every fifth line within the required margin.

One of the more specific objects of my invention is to provide means by which this 25 may be readily accomplished. To this end I have provided means by which the margin stop mechanism is automatically controlled from the line spacing mechanism so that every, say, fifth actuation of the latter 30 is operative to render the margin stops ineffective to arrest the carriage at its normal point of arrest, and permit it to move beyond said point to write the requisite 35 number within the margin.

A further object of the invention is to provide means in the nature of an attachment that may readily be applied to existing machines on the market to effect the results stated without modifying, or materially modifying, the structural features of 40 such machines as they now exist.

To the above and other ends, which will hereinafter appear, my invention consists in 45 the features of construction, arrangements of parts and combinations of devices set forth in the following description and particularly pointed out in the accompanying claims.

50 In the accompanying drawings, wherein like reference characters indicate corresponding parts in the different views,

Figure 1 is a front elevation of the carriage of an Underwood machine equipped 55 with the devices of my invention.

Fig. 2 is a like fragmentary view of the same showing the left-hand portion of the carriage, the automatically controlled means being locked in ineffective or inoperative position.

60

Fig. 3 is a fragmentary top plan view partly in section of the parts represented in Fig. 2.

In the present instance I have shown my invention embodied in an Underwood machine in which the invention may be readily incorporated without changing, or materially changing, the structural features of that machine. It should be understood, however, that the invention may be embodied in various other styles of machine with equal facility.

Only so much of an Underwood machine is shown as may be necessary to illustrate my invention in its embodiment therein.

75

Thus the carriage, designated as a whole by the reference numeral 1, carries a cylindrical platen 2 adapted to receive the usual case shifting movement relatively thereto, the carriage being nonshiftable but mounted in the usual manner to travel from side to side of the machine over the top plate. A line spacing wheel 3 is secured to the platen shaft 4. A line space pawl 5 is formed as a part of a carrier 6 pivoted at 80 7 to a spring-returned slide 8. This slide is mounted in a housing 9 on the left-hand side of the platen frame to slide fore-and-aft of the machine. A leaf spring 10 is secured at one end, as at 11, to the slide and 85 bears down at its free end against the carrier 6 of the line spacing pawl. This results in forcing the pawl to engage the teeth of the wheel 3 when the adjustable controlling member 12 permits such engagement to 90 be effected. A line spacing and carriage return lever, designated as a whole by the reference numeral 13, is pivotally mounted on the carriage to turn on a vertical axis around a shouldered screw pivot 14. This 95 hand lever is provided with a finger piece 15 by which it is actuated, and with a crank arm 16 which co-acts with the forward end of the spring returned slide 8. A movement of the finger piece 15 from left to right is 100 effective to actuate the slide 8 and produce a line spacing movement of the platen. The extent of this line spacing movement may be controlled in the usual manner by the setting or adjustment of the member 12 105

110

hereinbefore referred to. Continued pressure exerted on the finger piece results in the carriage being moved to the right until it is arrested by a margin stop 17 on the 5 carriage co-acting with the left-hand face of the usual adjustable margin stop 18 carried by the frame of the machine. The margin stop 17 is formed by the forwardly bent end of a lever 19 which extends longitudinally of and parallel with the front cross bar 20 of the carriage, and beneath the forwardly extending flange 21 of said cross bar. The lever 19 is pivoted at 22 to the cross bar and extends upwardly at its right-hand end to form a finger piece or key 23. A depression of the key is effective to elevate the left-hand end of the lever against the force of a leaf spring 24, thus carrying the lever to the dotted line position where 10 the stop 17 is moved out of co-operative relation with the stop 18. The carriage may then be moved to the right beyond its normal point of arrest where the stops 17 and 18 co-act, and is finally arrested by the stop 17 co-acting with the final stop 25. The 15 operator may thus at any time write within the margin by depressing the margin release key 23. After the stop 17 has passed to the right of the stop 18, and pressure on the key 23 has been released, the stop 17 in 20 the movement of the carriage to the left will contact with the right-hand bevel face 26 of the stop 18 and be lifted and thus automatically pass the stop 18 without obstructing the movement of the carriage.

The construction thus far described constitutes part of the ordinary Underwood machine.

In order to relieve the operator from the 40 necessity of constantly bearing in mind how many lines have been written, and when it is necessary to write the number of a line within the margin at given intervals, I have provided means for automatically releasing the margin stops at such given intervals, thus bringing the carriage at once to the 45 point where the number of the line may be written within the margin. And the very act of a carriage automatically moving beyond its normal point of arrest is effective to 50 warn the operator to write the requisite number within the margin before proceeding to write the line.

The automatically operating means in 55 question, in the present instance, comprises a rotative controlling device or star wheel 27 mounted to turn on a shouldered pivot screw 28 secured to the front face of the cross bar 20 of the carriage. The teeth of the star wheel turn through a cut-out in the flange 21, as indicated at 29, and one of the teeth normally extends into the path of movement of the line spacing lever 13, as shown in Fig. 1. There are five teeth *a*, *b*, *c*, *d* and *e* on the 60 star wheel in the present instance, so that five

intermittent movements transmitted to the wheel by the line spacing lever is effective to make a complete turn of the wheel.

Secured to the rear face of the star wheel 27 is a rotative actuating device, cam or wiper, designated as a whole by the reference numeral 30. This device in the present instance is formed with five faces, *f*, *g*, *h*, *i* and *j*. Each of these faces co-acts with the flat upper edge 31 of a combined actuating 75 and detent lever 32, tending to restore the wheel 27 to and hold it in any one of the five different positions to which the wheel may ordinarily be moved, as will hereinafter appear. It will be observed that the radial 80 distance of all the surfaces or faces, *f*, *g*, *h* and *i*, from the center of the wheel is the same, whereas the face *j* is formed on the end of an extension of the wiper 30, and its radial distance from the center of the wheel 85 is greater than that of the other faces.

The lever 32 is pivoted on a shouldered pivot screw 33 secured to the front cross bar 20 of the carriage. The right-hand end of this lever extends downwardly and then upwardly to form a finger 34 which lies beneath the inner end of the release lever 19 in a position to co-act therewith to shift the latter from the full to the dotted line position shown in Fig. 1. It should be understood that the spring 24 is effective not only to normally maintain the release lever 19 in the full line position in Fig. 1, but also to exert its force through said lever against the lever 32 to force the left-hand end of the latter upwardly. The effect of this is to cause the flat face 31 on the lever 32 to bear against one of the flat faces *f*, *g*, *h*, *i* or *j* of the wiper and tend to maintain the wheel in a position where one of the teeth thereon will be maintained in the path of the line spacing lever, as shown in Fig. 1.

While the spring 24 and the levers 19 and 32 may be sufficient in themselves to act as a 90 detent mechanism for the purpose described I prefer to add a spring detent 35 formed substantially as shown and secured at one end, as at 36, to the flange 21. The free end portion of this spring is adapted to bear 95 against the teeth of the star wheel 27 and tends to assure the movement of the wheel to, and to hold it against accidental displacement from, any one of the several positions it is to assume.

Let it be assumed that the parts are positioned as represented in full lines in Fig. 1 and that the first line has not been written. The operator will grasp the finger piece 15 moving it to the right thereby effecting a 100 line spacing operation and returning the carriage to the right to begin the first line. The effect of this is to turn the star wheel 27 one step, thus moving the detent face *i* 105 out of co-operation with the lever 32 and bringing the detent face *h* into co-operation 110

therewith; the spring-pressed lever 32 and detent spring 35 aiding in a completion of the movement of the star wheel. This advances the tooth *b* one step to the former position of the tooth *c*, and the tooth *a* will be brought to the former position of the tooth *b*, shown in Fig. 1. As the line spacing lever returns to its normal position it will co-act with the tooth *a* to effect a slight backward turning movement of the wheel sufficient to enable the line spacing lever to return to normal position without obstruction from the wheel. This slight backward clearing movement of the wheel is effected against the pressure of the spring detents, as will be understood from an inspection of Fig. 2. As soon as the line spacing lever has, in its return movement, cleared the engaged tooth *a* of the wheel it will be slightly advanced again by the spring detents to elevate the depressed tooth *a* into the path of the lever, so that on the next actuation of the latter the wheel may be advanced another step.

It will be understood that while this first step in the advance of the wheel effects a very slight movement of the levers 32 and 19 on their pivots this movement is insufficient to elevate the margin stop 17 to a point where it will clear the stop 18.

The intermittent movements of the wheel 27 and the member 30 will continue until the fifth line spacing operation has taken place when the wiper is brought to the dotted line position shown in Fig. 1, with the face *j* co-acting with the lever 32. This results in moving the levers 32 and 19 to the dotted line position in Fig. 1, and in elevating the stop 17 to clear the stop 18 and enable the carriage to move beyond the normal point of arrest and to continue such movement until the stop 17 co-acts with the final stop 25. The operator will then write the numeral "5" within the margin and continue as before until the tenth line spacing operation has taken place when the carriage has again automatically positioned to write the numeral "10" within the margin, and so on.

I have provided simple and efficient means by which the operator may, when desired, render and maintain ineffective the automatically operating means for controlling the margin stop mechanism. Thus, a controlling device in the nature of a screw 37, formed with a mutilated head, is threaded 55 into a tapped opening in the front cross bar of the carriage. The mutilated head provides a flat contact face 38 which is adapted to co-act with the rear side of a tooth of the star wheel when the screw is turned from the position shown in Fig. 1 to that illustrated in Fig. 2. The effect of this movement of the screw is to produce a slight backward movement of the wheel from the position shown in Fig. 1 to that illustrated 60 in Fig. 2. This movement of the wheel is

sufficient, as will be seen from an inspection of Fig. 2, to maintain the teeth of the star wheel out of the path of the line spacing lever. Therefore, a movement of the lever at this time has no effect on the star wheel 70 or the parts controlled thereby, and the automatically operated means are rendered and maintained ineffective or inoperative. When the screw is returned to the position shown in Fig. 1, the detent devices will return the wheel to its normal position, shown in said figure. At this time the teeth of the wheel may move freely past the flat face 38 of the mutilated head.

In the Underwood machine a full stroke 80 of the line spacing lever is given irrespective of the extent of line spacing movement transmitted to the platen thereby. It will be understood therefore that the automatic control of the margin stop mechanism is 85 always the same, whether the regulating device for a line spacing mechanism be set for half spacing, full spacing or double spacing, and that this change in the character of line spacing does not affect the automatically operating means in any way.

From the foregoing description it will be seen that I have provided simple and efficient means of the character specified; that such means are in the nature of attachments 95 that may be readily incorporated in existing machines without changing, or materially changing, the structural features of such machines as they now exist, and that by the automatic control of the margin stop mechanism in the manner described I relieve the operator of the constant distraction due to the care which must ordinarily be exercised in numbering the lines, and in remembering to keep track of the given intervals when the 100 lines should be numbered.

I have shown but one form of mechanism embodying my invention, but am aware that the invention may be clothed in various forms and may be variously modified to 105 afford an application thereof to other styles of machines than that shown, and that such changes may be made without departing from the spirit and scope of my invention.

What I claim as new and desire to secure by Letters Patent, is:

1. In a typewriting machine, the combination of a nonshiftable carriage, a platen adapted to receive a case shifting movement 120 relatively thereto, means for arresting the carriage in a plurality of its return movements at the normal given predetermined point of arrest, and automatically operating means carried wholly by said nonshiftable carriage for enabling the carriage to move beyond such predetermined point to write within the margin once in every given plurality of return movements.

2. In a typewriting machine, the combina- 130

tion of a carriage, margin stop mechanism including a hand-actuated margin release key at the front of the machine and which is operable at will, and automatically operating means for actuating said release key.

3. In a typewriting machine, the combination of a nonshiftable carriage; line spacing mechanism; coacting margin stops; and automatically actuated means for rendering said margin stops ineffective to arrest the carriage, said means including an automatically and intermittently actuated wiper carried directly by said carriage.

4. In a typewriting machine, the combination of a carriage, margin stop mechanism including a hand-actuated margin release key operable at will, automatically operating means for actuating said release key, and means operable at will for maintaining ineffective said automatically operating means without interfering with the effectiveness of said release key to be operated at will.

5. In a typewriting machine, the combination of a nonshiftable carriage; line spacing mechanism; coacting margin stops; and automatically actuated means for rendering said margin stops ineffective to arrest the carriage, said means being carried directly by the carriage and including an automatically and intermittently actuated wiper, and means controlled by said wiper for moving one of said margin stops out of coöperative relation with the other margin stop.

35. 6. In a typewriting machine, the combination of a carriage; line spacing mechanism; coacting margin stops; and automatically actuated means for rendering said margin stops ineffective to arrest the carriage, said means including an automatically and intermittently actuated rotative wiper that is always advanced in the same direction, a hand actuated margin release key at the front of the machine and which may be actuated by hand at will, and means controlled by said wiper for actuating said key.

7. In a typewriting machine, the combination of a nonshiftable carriage; a shiftable platen carried thereby; line spacing mechanism; coacting margin stops; and automatically actuated means for rendering said margin stops ineffective to arrest the carriage, said means including an intermittently actuated star-wheel carried directly by said nonshiftable carriage, and means controlled by said star-wheel and carried directly by the carriage for controlling one of said margin stops.

8. In a typewriting machine, the combination of a nonshiftable carriage, a cylindrical platen shiftable thereon, line spacing mecha-

nism therefor, coöperative margin stops one of which is carried by a lever on the carriage, and means carried directly by said carriage and controlled by said line spacing mechanism for automatically shifting said lever to displace the margin stop carried thereby out of coöperative relation with its companion margin stop.

9. In a typewriting machine, the combination of a carriage, two independently fulcrumed levers arranged in line lengthwise of the carriage and operatively connected at their ends, one lever carrying a carriage arresting stop at its inner end and a finger piece at its outer end, a wiper which coacts with the other lever, a star-wheel which turns said wiper, a line spacing lever acting directly on the teeth of said star-wheel to turn it, and a carriage arresting stop with which said first mentioned stop coacts.

10. In a typewriting machine, the combination of a carriage, a line spacing lever, a star-wheel arranged adjacent to said line spacing lever, means for insuring that a tooth of said wheel shall be in the path of said lever so as to be struck thereby, a rotative wiper having a plurality of faces equidistant from its center of rotation and a single face formed on an extension, a lever constantly pressing against one of said faces, a second lever overlapping the first mentioned lever and carrying at one end a carriage arresting stop and at its opposite end a finger piece, and a second coacting carriage arresting stop.

11. In a typewriting machine, the combination of a carriage, two levers of the first order overlapping at their inner ends and extending substantially the whole length of the carriage, one lever carrying a carriage arresting stop at its inner end and a finger piece at its outer end, a vertically arranged star-wheel turnable intermittently in a plane parallel to the plane of movement of said levers, a wiper mounted to turn on the axis of said star-wheel and in constant engagement with one of said levers, a horizontally sweeping line spacing lever adapted at each inward stroke to contact with an upstanding tooth of said star-wheel, and a carriage arresting stop with which said first mentioned stop is adapted to coact.

Signed at the borough of Manhattan, city of New York, in the county of New York, 115 and State of New York this 6th day of June, A. D. 1918.
